FIG. 1

FIG. 2

FIG. 3

FIG. 4

FIG. 5

FIG. 6

FIG. 1 is a perspective view of a drafting table or the like embodying my new design, this figure showing the table of the plotter in an inclined position.

FIG. 2 is a front elevational view of the plotter of FIG. 1 and shows the table of the plotter in its horizontal position.

FIG. 3 is a top plan view of the plotter of FIG. 1 with the table of the plotter in this figure being shown in its horizontal position.

FIG. 4 is a rear elevational view of the plotter of FIG. 1 with the table of the plotter in this figure being shown in its horizontal position.

FIG. 5 is a side elevational view of the plotter of FIG. 1 with the table of the plotter in this figure being shown in its horizontal position.

FIG. 6 is a side elevational view similar to FIG. 5 but showing the table of the plotter in its vertical position.

I claim:

The ornamental design for a drafting table or the like, substantially as shown.
